Victoria, AustraliaApplication May 1, 1946, Serial No. 666,343
In Australia March 17, 1945

10 Claims. (Cl. 5—334)

1

This invention relates to perambulator covers, cot covers, eiderdown covers or like bed coverings having wool, kapok, or like warmth retaining linings or fillings.

It is recognized that eiderdown covers or other bed coverings, while providing warmth and a decorative finish to the bed, have an inherent disadvantage in that it is practically impossible to wash the said coverings in view of the tendency of the filling or lining to stain the fabric.

Moreover, the filling, upon the washing of the bed covering, takes considerable time to dry, while the ironing of the covering, due to its irregular surface, constitutes a very difficult and tedious operation.

Perambulator covers and cot covers readily become soiled, but in view of the above mentioned washing and ironing difficulties, cannot be maintained in the required state of cleanliness without sacrificing the normal colour and appearance of the same.

Now the principal objective of this invention is to eliminate the above stated disadvantages by the provision of an eiderdown cover or other bed covering that can be readily washed and maintained in a state of cleanliness without detracting from its appearance or colour.

With the above stated object in view, there is provided according to this invention, a fabric or like bed covering having a multiple number of receptacles, pockets or tunnels, for removable warmth-retaining pads formed by sewing fabric strips to one side of a sheet of fabric material.

The warmth-retaining pads are normally positioned in the receptacles, tunnels or pockets and provide substantially the same warmth as a conventional eiderdown cover or other bed covering with the additional and important advantage that the pads are readily removable to permit the convenient washing and ironing of the covering and subsequent reinsertion of the pads.

The accompanying drawings illustrate a practical embodiment of the invention as applied to an eiderdown cover or like bed covering.

In these drawings:

Fig. 1 is a view in perspective of the bed covering as seen from the upperside thereof.

Fig. 2 is a fragmentary sectional view on the plane 2—2 in Fig. 1.

Fig. 3 is a fragmentary perspective view, partly in section, at the underside of a corner of the bed covering shown in Fig. 1.

Figs. 4 and 5 are sectional views of several modified forms of the present invention.

Referring to Figs. 1 to 3 of the drawings which

2

illustrate the bed covering in the form of a perambulator cover or eiderdown cover, said covering is comprised essentially of an upper sheet 5 of fabric material continuous in length and width and turned under at each end 6 to provide two continuous marginal flaps 7 on the underside 8 of the covering one at each end of said covering.

There is provided on the underside 8 of the covering a plurality of aligning transversely disposed receptacles or pockets indicated generally at 10 throughout the several figures of the drawings, and arranged in continuous rows as viewed in Figs. 1 to 3. Said pockets 10 are formed mainly by the attachment of separate transversely disposed strips 11 of fabric material to the main upper sheet 5 of the bed covering. The flaps 7 at each end of the bed covering cooperate with the main portion of sheet 5 to form receptacles 10 or pockets at each end 6 of the bed covering.

In that form of the invention shown in Figs. 1 through 3, each receptacle or pocket-forming strip 11 is disposed transversely of the underside of the sheet 5 and is secured to said sheet 25 by a row of stitches 13 which extends transversely of the sheet and intermediate and parallel to the longitudinal side edges of said strip 11, all as clearly shown in Fig. 2. The strips 11 are arranged in parallel spaced relation and, with the material of the sheet 5 and rows of stitches to be hereinafter described, form a plurality of rows of receptacles or pockets 10 which extend in parallel rows transversely of the sheet 5 and from end to end thereof. In order to form the individual receptacles or pockets 10, spaced parallel rows 30 of stitches 13a are provided, which rows extend longitudinally of the sheet as best shown in Fig. 1, and pass through longitudinally-spaced portions of each of the transversely disposed, pocket forming strips 11. Hence, the receptacles or pockets 10 are defined by material of the sheet 5 and the material of the strips 11, and by the transversely-extending rows of stitches 13, and the spaced, longitudinally-extending rows of 35 stitches 13a. Each receptacle or pocket 10 is open at one end, and is closed at its opposite end by stitches 13, and at its two sides by stitches 13a.

The open ends of adjacent rows of receptacles or pockets 10 preferably face each other in spaced, parallel relation as best shown in Fig. 2, and such open ends, being disposed in alignment, are closed by flaps which are formed by portions of strips of material 14 sewed to the underside of the sheet 5 in spaced, parallel rows by stitches 50 13b, these flaps 14 and the rows of stitches 13b

extending transversely of the sheet 5 and between the spaced transverse rows of pocket forming strips 11 and stitches 13. Each row of stitches 13b extends longitudinally of each strip 14 and intermediate and parallel to the longitudinal side edges thereof, to provide pocket closing flaps adapted to be tucked into and close the open ends of the adjacent rows of pockets located on opposite sides of each strip 14. It is to be noted that the flaps formed by the strips 14 may be readily moved from the position shown in Fig. 2 to open the ends of the pockets by moving about the line of attachment of the stitches 13b so as to permit ready access to the receptacles or pockets 10.

The rows of pockets 10a at the ends of sheet 5 differ slightly from the pockets 10 of the remaining rows, in that the material of the sheet 5 constitutes the top of the pockets in these end rows, the bottoms of these end rows are formed by the inturned flaps 7, the outer ends of these pockets are defined by stitches 13c, the sides of each pocket are defined by stitches 13a, and the open ends of these pockets are closed by extensions 11a of pocket forming strips 11, all as clearly shown in Fig. 2.

As best shown in Fig. 2, and as explained above, the receptacles or pockets 10 and 10a are preferably open at one end only, but in the modified construction illustrated in Fig. 4, the pockets 10b are of tunnel formation, i. e. open at both ends. In this form of the invention, pocket-forming strips 11b are secured to the underside of sheet 5 in parallel, spaced relation and transversely of said sheet by means of longitudinally extending rows of stitches corresponding to the rows of stitches 13a of the form of the invention illustrated in Figs. 1 through 3. No transversely-extending rows of stitches corresponding to the rows of stitches 13 of Figs. 1 through 3 are employed in this modified form of the invention, as it is desired to have both ends of the receptacles or pockets 10b open. The adjacent open ends of the several rows of pockets 10b face each other in spaced, parallel relation, and such open ends, being disposed in alignment, are closed by flaps which are formed by portions of strips of material 14a sewed to the underside of the sheet 5 in spaced, parallel rows by stitches 13d, these flaps 14a and the rows of stitches 13d extending transversely of the sheet 5 and between the spaced transverse rows of strips 11b. Each row of stitches 13d extends longitudinally of each strip 14a and intermediate and parallel to the longitudinal side edges thereof, to provide pocket closing flaps adapted to be tucked into and to close the open ends of the adjacent transverse rows of pockets 10b located on opposite sides of each strip 14a. It is to be noted that the flaps formed by strips 14a may be readily moved from the positions shown in Fig. 4 to open the ends of the pockets 10b by moving about the line of attachment of the stitches 13d so as to permit ready access to the receptacles or pockets 10b.

In each pocket 10, 10a, or 10b there is disposed a closed bag or pad 15 of fabric material filled with wool, cotton wool, kapok, down or other warmth retaining material. Said pads 15 are dimensioned and shaped to neatly fit within the receptacle or pockets 10, 10a, or 10b. Upon the flaps 14 or 14a being withdrawn from the open ends of the receptacles or pockets, the pads 15 normally positioned within the latter, can be readily grasped and removed from the receptacles

or pockets to permit the washing of the bed covering.

As there are only in effect two thicknesses of material upon the removal of the pads 15, it is a relatively simple matter to wash, iron or otherwise launder the bed covering.

Incidentally, the free withdrawal of the receptacle or pocket flaps 14 or 14a opens the receptacles or pockets for the reinsertion of the pads.

If required, and as illustrated in Fig. 5, the flaps 14 and 14a may be provided with buttons 16 to engage button holes 16a in the outer adjacent section of material forming one wall of each receptacle or pocket 10 or 10b.

As the receptacles or pockets 10, 10a, or 10b are formed on the underside of the bed covering, the upper surface presents a conventional pattern when the receptacles or pockets 10 are filled with pads 15 as viewed in Fig. 1.

In the embodiments described and illustrated the pads 15 consist of closed bags of textile material stuffed with wool, cotton wool, kapok, down or the like, but pads composed of pieces of blanket, cloth, felt or other warmth-retaining material may be used, if so desired.

As illustrated in Figs. 1 and 3, there is a marginal extension 17 of the sheet 5 devoid of receptacles or pockets at each side of the bed covering.

The marginal extensions 17 facilitate the retention of the bed covering upon the bed, by folding said extensions under the bed clothes or mattress.

Herein the term "bed covering" designates any covering such as a perambulator or cot cover, eiderdown cover or the like bed covering.

I claim:

1. A bed covering of the type herein specified, comprising a continuous sheet of fabric material, separate, transversely-disposed strips of fabric material secured upon one side of the sheet in substantially parallel relation, each strip also being secured to said one side of said sheet at spaced intervals longitudinally of the sheet to form with the sheet pockets to receive warmth-retaining pads, and flaps secured to said one side of the sheet and forming releasable closures for said pockets.

2. A bed covering as claimed in claim 1, where-in the strips are overlapped to form the releasable closure flaps.

3. A bed covering comprising a sheet of fabric material, strips of fabric material disposed upon one side of said sheet in substantially parallel relation transversely of said sheet, pockets formed by sewing each strip to said one side of said sheet throughout the length of each strip and at spaced intervals longitudinally of said sheet and strip to form with said sheet a plurality of pockets on said one side of said sheet, warmth-retaining pads within said pockets and readily removable therefrom, and closure flaps secured to said one side of the sheet and closing said pockets.

4. A bed covering comprising a sheet of fabric material, strips of fabric material disposed in parallel relation and extending transversely of the sheet upon one side of said sheet, pockets on said one side of said sheet comprised of portions of the sheet and adjoining portions of said strips formed by sewing the strips throughout their length and transversely of said sheet and at spaced intervals longitudinally of said sheet and strip, warmth-retaining pads within said pockets and readily removable therefrom, and

closure flaps secured to said one side of said sheet and closing said pockets.

5. A bed covering as defined in claim 4, wherein the closure flaps comprise separate strips secured to said one side of said sheet parallel to said first mentioned strips and transversely of said sheet.

6. A bed covering as defined in claim 4, wherein the closure flaps comprise extensions of the strips of fabric material.

7. A bed covering comprising a sheet of fabric material, strips of fabric material disposed in parallel relation and extending transversely of the sheet upon one side of said sheet, rows of pockets comprised of portions of said sheet and said strips formed by sewing the strips transversely of said sheet and at spaced intervals longitudinally of said sheet, warmth-retaining pads within said pockets and readily removable therefrom, and flaps sewed to the said one side of said sheet and extending transversely thereof and comprising releasable closures for the pockets.

8. A bed covering comprising a sheet of fabric material, strips of fabric material disposed in parallel relation and extending transversely of said sheet upon one side of said sheet, pockets formed by sewing each strip to the sheet at spaced intervals transversely to the length of the strip and along a line between and parallel to the lateral edges of the strip, warmth-retaining pads within said pockets and readily removable therefrom, and flaps sewed to said one side of said sheet and comprising releasable closures for the pockets.

9. A bed covering comprising a rectangular sheet of fabric material, fabric strips disposed upon one side of the sheet in substantially parallel relation, rectangular pockets on said one side of said sheet open at one edge and comprised of portions of said sheet and of the strips and formed by sewing the strips to the sheet along

5

lines parallel to the lengths of the strips and along lines spaced apart and at right angles to the lengths of the strips, and flaps sewed to said one side of said sheet and comprising closures for the open edges of the pockets.

10. A bed covering comprising a substantially rectangular sheet of fabric material, strips of fabric material of less length than the width of the sheet between the opposite side edges thereof and transversely disposed on one face of said sheet in substantially parallel relation, said strips terminating within the width of the sheet at substantially equal distances from said opposite side edges thereof, pockets formed by sewing each strip along the length thereof and at spaced intervals longitudinally of said sheet and strip, warmth-retaining pads within said pockets and readily removable therefrom, closure flaps sewed to said one side of said sheet and closing said pockets, and plain marginal portions on the sheet extending between the ends of the strips and each opposite side edge of said sheet.
